UNITED STATES PATENT OFFICE.

BURT J. FARR AND MOSES H. WESTBROOK, OF BATTLE CREEK, MICHIGAN.

MACHINE FOR REBORING OR REFINISHING CYLINDERS.

Application filed September 15, 1924. Serial No. 737,679.

The invention relates to machines for re-boring or refinishing cylinders.

In railroad practice, it becomes necessary from time to time to re-bore compressors, which usually include a steam-cylinder and an air-cylinder, and when the compressor is of the compound type, two steam cylinders and two air-compressors secured to an intermediate frame. Heretofore, it has been necessary, in re-boring or refinishing a cross compound air-compressor, to dismantle substantially the entire compressor and to separate the cylinders from the intermediate frame and then separately and successively re-bore them. It usually took from seven to twelve hours to accomplish this.

One object of the invention is to provide a machine for reducing the time necessary for the re-boring operation of a compressor.

In re-boring these compound cylinders, it is important that the aligned cylinders should remain truly coaxial to prevent excessive wear on the piston-rod packings and to insure the free operation of the pistons and rods in the cylinders, and another object is to provide an improved re-boring machine by which this coaxiality will be insured.

Another object is to provide an improved machine for that purpose, by which the re-boring operations can be easily and accurately effected.

Other objects of the invention will appear from the description.

The invention consists in the several novel features hereinafter set forth and more particularly defined by claims at the conclusion hereof.

In the drawings: Fig. 1 is a side elevation. Fig. 2 is an end elevation. Fig. 3 is a detail of the gearing for driving one pair of boring bars. Fig. 4 is a detail section of one of the guide bushings for the inner ends of the boring-bars. Fig. 5 is a perspective of one of said bushings. Fig. 6 is a plan, parts being shown in section. Figs. 7 and 8 are longitudinal sections on an enlarged scale through the ends of one of the boring-bars and associated parts. Fig. 9 is a section on line 9—9 of Fig. 8. Fig. 10 is a section on line 10—10 of Fig. 7.

The invention is exemplified in connection with a "Westinghouse" cross-compound air-compressor comprising a high-pressure steam-cylinder *a*, coaxial with a low-pressure air-cylinder *b* and a low-pressure steam cylinder *c*, which is coaxial with the high-pressure air-cylinder *d*. Cylinders *a* and *c* are integrally formed and cylinders *b* and *d* are likewise. All of the cylinders are secured to an intermediate cast frame *e*. This cylinder-structure, as exhibited, is of well-known construction, the cylinder-heads, pistons and valve-mechanisms having been removed to provide access to the cylinders for re-boring. It is not necessary, however, in the use of the machine to separate the cylinders from one another or from the connecting frame.

The invention is exemplified in a machine by which all four of the cylinders of a cross-compound air-compressor of this type may be simultaneously bored or refinished. A table 10 supports the compressor, while it is being re-bored or refinished, and the cylinder-structure of the air-compressor is bolted to the table, as at 12, during a re-boring operation. Table 10 is mounted on and fixed to frames 11. Brackets 13 are secured to the frames 11 respectively to support base-plates 14 for electric motors 15 and 16 for driving the several units of the machine. Switches 15^a, 16^a, are provided to separately control said motors.

The re-boring mechanism comprises a head-frame 18 adapted to be secured to the outer ends of cylinders *a*, *c*, and a similar frame 19 adapted to be secured to the outer end of cylinders *b*, *d*. These frames are adapted to be secured to the cylinders in lieu of the pump flanges and cylinder-heads which have been removed from the cylinders, preliminary to re-boring the latter.

A boring-bar 20^a has its outer end journaled in the bearing 22 in frame 18 and is provided to rotate a tool-carrier 24^a in the cylinder *a*. A boring-bar 20^c has its outer end journaled in bearing 21 of frame 18 and is provided to operate a tool-carrier 24^c in cylinder *a*. A boring-bar 20^b has its outer end journaled in bearing 21 of frame 19 and operates a rotary tool-carrier 24^b in the

cylinder *b*. A boring-bar 20^d has its outer end journalled in bearing 22 of frame 19 to operate a tool-carrier 24^d in cylinder *d*.

The inner end of the boring-bars 20^a, 20^b, 20^c, and 20^d are journalled in bushings 23 respectively which are usually formed of brass and are each secured to a screw-cap *e*² which is adapted to be screwed onto the outer end of one of said casings. These bushings are split so as to be contractible by and tapered to fit, and are adapted to be inserted in the usual stuffing-box casings *e*¹ in frame *e* of the cylinder structure, through which the piston-rods between the pump and steam cylinders slide. Preparatory to the insertion of these bushings, the usual packing and adjustable glands of the packing-boxes for the piston-rods are removed and the packing-box casings are left in place, so that when the bushings 23 are inserted, the inner ends of aligned boring-bars will be truly and coaxially journalled in the cylinders. These boring-bars are insertable into the cylinders respectively from the outer and opposite ends of aligned cylinders while they remain in connected relation to the head-frames.

The frames 18 and 19 comprise ring-portions which are provided with holes 26 which are adapted to register with the bolt-holes in the cylinder-structure of the compressor for the bolts which attach the cylinder-heads thereto, so that the frames 18 and 19 may be rigidly, detachably and quickly secured to the cylinders. In order to accurately support the outer end of the boring-bars axially in the cylinders, tapped lugs 27 are formed on the frames 18 and 19 for radial thumb-screws 28, by which the supporting frames may be accurately adjusted to centrally position the boring bars in the cylinders. Frames 18 and 19 are recessed outwardly so that the tool-carriers at the beginning of an operation can be disposed outwardly of the cylinders so the tools will commence to cut at the outer ends of the cylinders.

The boring-bars for cylinders *a* and *b* are aligned with each other and the bars for cylinders *c* and *d* are also aligned. The inner end of each boring-bar is connected to its aligned bar by a coupling 29 which is provided with ribs 30 and 31 to enter recesses 32 in the bars respectively. This coupling forms a driving connection between the coaxial boring-bars so that one will be driven from the other.

Boring-bars 20^c and 20^d are driven from motor 16 and boring-bars 20^b and 20^a are driven from motor 15, by means of gear-reductions which are similar in construction. Each of said reductions comprises a pinion 33 on the motor-shaft; a gear 34, meshing with said pinion 33, and fixed to drive a pinion 35 which meshes with a gear 36; a

pinion 37 fixed to rotate with gear 36; and a gear 38 driven by pinion 37 and fixed to one of said boring-bars. Each of these gearings, with the exception of pinion 33, is enclosed in a housing which is composed of a flanged member 40 and a side plate 41 which are cross connected by spacer-bolts 42. Each housing supports one of these gearings and is pivotally held on the hub of gear-wheel 38 and is held against rotation by a fork 44 which is provided with slots 45 to receive studs 46 on the housing. Fork 44 is fixedly supported by the post 47 which is adjustably supported from one of the motor base-plates 14. The studs 46 can be swung out of the slots 45, so that the head frames may be readily withdrawn from the cylinder structure.

Each tool-carrier comprises a hub 50, which is longitudinally slidable on one of the boring-bars and is caused to rotate therewith by a block 51 which is slidably held in a slot 52 in the boring bar and is held and locked to said hub by a lug 54 fitting in a recess 55 therein and also by a screw 56. Each hub 50 is provided with arms 57 in which a boring or other suitable finishing tool 60 is adjustably held by any suitable or well known means in position to operate on the inner periphery of one of the cylinders.

Each boring-bar is provided with a device 95 for automatically feeding the tool longitudinally of the cylinder. This device comprises a spindle 61 which is provided with a screw 62 interfiting with a female thread 63 on the key-block 51 attached to one of the tool carriers. This spindle is driven from its boring-bar by a gear-train comprising a pinion 64 which is fixed to rotate with the bar by a screw-thread 65; a double idler pinion 66, 67 mounted on a shaft 68; a pinion 69 loosely held on the spindle 61; and a clutch-collar 70 which is connected by a spline and way 71 to the spindle, and has clutch-teeth interfiting with similar teeth on the pinion 69. Each shaft 61 is rotatable in its boring-bar and held against longitudinal movement by a shoulder 24^a confined in a recess in said bar and held against outward movement by a washer 24^b and the inner end of the hub of gear 64. Clutch-collar 70 is slidably movable into and out of engagement with pinion 69, so that whenever it is desired to position a tool-carrier in the cylinder independently of the automatic feed or retracted, it can be quickly done by disengaging the collar 70 from said pinion 69 and rotating the spindle directly by means of a crank 72 fixed to its outer end and independently of the gear-train. A gear-housing 73 encloses gears 64, 66, 67, and 69. Shaft 68 is mounted in a plate 74 which encircles the boring-bar with which it is associated. This plate is

positioned against one of the sides of one of the gear-housings 40, 41 by a collar 75, which is screw-threaded to the outer end of the boring-bar. Lugs 76, secured to the housings 5 respectively are each provided with a fork 77 which straddles one of the shafts 68 to hold the latter and the pinions thereon against bodily rotation with the boring bar and spindle therein. The shafts 68 for the 10 feed mechanism for boring bars 20^a and 20^b are directly secured in frames 18 and 19 respectively.

Each of these devices causes one tool-carrier to be fed inwardly in the cylinder while 15 the bar is driven and exemplifies an automatic feed to move the tool longitudinally of the cylinder, which is removable with one of the boring-bars and head-frames, so that the feed-device, bar and frame will 20 remain in connected relation, so they may be conjointly removed from and mounted on the cylinder-structure.

The operation of the improved machine will be as follows: When a cross-compound 25 compressor-cylinder is to be bored, the compressor is removed from the locomotive and its heads, with the valves therein and piston rods, are removed from the compressor, leaving the cylinders connected to the frame 30 *e*, so that the co-relation of the cylinders will not be disturbed, and the piston-rod packings and their followers are removed from the frame *e*. The boring-bars are 35 passed through the cylinders from the outer ends thereof respectively, and the frames 18 and 19 are accurately positioned by screws 28, so the boring bars will be truly coaxial with the cylinders. Bushings 23 will be inserted in the packing-box casings 40 in the frame *e*, so that each boring-bar will have a bearing at its inner end in one of these bushings and in one of the head-frames 18, 19 at its outer end. The bolts for attaching the compressor-heads will then be 45 used to secure the frames 18, 19 to the cylinder-structure. As the boring-bars are inserted into the cylinders from opposite ends, the couplings 29 will be placed between the contiguous ends of the aligned boring bars, 50 so that one will be driven from the other. When the head-frames 18 and 19 are secured in operative position, the housings 40, 41, for the gear-reductions will be swung so 55 their studs 46 will pass into engagement with the forks 44 on the stationary supporting structure, to operatively connect the gears 34 to the pinions on the motors. This provision is made so that the frames 18, 19 and the boring-bars carried thereby can be 60 disconnected from the motor while the boring-bars are being inserted into and removed from the cylinders. In starting an operation, the tool-carriers will be positioned in the recesses of frames 18, 19, so the tools 65 will be disposed outwardly of the ends of

the cylinders. When the machine has been thus connected to the compressor, the motors may be singly or collectively operated under control of switches 15^a, 16^a. The boring-bars 20^b, 20^c will be driven to rotate the 70 tools carried thereby and bars 20^a and 20^b will be driven by couplings 29. Simultaneously, the tool-carriers will be fed progressively inwardly, so that the entire area of the cylinders will be re-bored or re-finished during the strokes of the tools. This feeding of the tools is effected by the rotation of the boring-bars, each of which drives the screw-spindle 61 therein through pinions 64, 66, 67, 69 and clutch-collar 70. 80 When the cylinders have been thus re-bored or re-finished, the clutch-collars 70 of the tool-feed devices can be disengaged from their pinions 69, so that the spindles 61 can be quickly retracted by cranks 72. Next, 85 the housings 40, 41 are disconnected from forks 44 and the frames 18, 19 are removed from the cylinders. Thereupon, the frames 18, 19 and mechanisms carried thereby can be removed from the cylinders and the latter can be removed for replacement.

In practice, it has been found that the time necessary to re-bore the cylinders of a cross-compound air compressor can be performed in approximately two hours, while under prior practice, so far as known to us, this work had required approximately from seven to twelve hours. The connections between the cylinders and the frame *e* are not disturbed, so that their relative positions will not be disturbed and the gaskets between them will not be destroyed, which sometimes occurs in practice when the cylinders are individually bored in accordance with prior practice. The invention also exemplifies a machine in which the true coaxiality of the cylinders, which is necessary to prevent undue wear of the packing boxes for the piston-rods, is readily attained, because the longitudinally aligned cylinders are bored by coaxial tool-carriers. The machine can be operated so as to individually re-bore the cylinders, or it may be used to simultaneously re-bore two aligned cylinders or to simultaneously re-bore four of the cylinders. Certain features of the invention are susceptible of use in connection with a compressor which comprises but one steam-cylinder and one air-cylinder.

The invention is not to be understood as restricted to the details set forth since these may be modified within the scope of the appended claims, without departing from the spirit and scope of the invention.

Having thus described the invention, what we claim as new and desire to secure by Letters Patent, is:

1. In mechanism for re-boring cylinders, the combination of a base for supporting a cylinder to be bored, a frame adapted to be

removably connected to and supported by the cylinder, a boring-bar carried by the frame, a motor mounted on the base, driving means for the bar carried by the frame and shiftable as a unit into driving relation with the motor and a tool-carrier mounted on the bar.

2. In mechanism for re-boring cylinders, the combination of a base for supporting the cylinders to be bored, a pair of frames 10 adapted to be removably connected to and supported by the cylinders, a pair of boring-bars carried by the frames a motor mounted on the base, driving means for the bars carried by the frame and shiftable as a unit in- 15 to driving relation with the motor and tool-carriers on the bars.

carriers on the bars.

3. In mechanism for re-boring cylinders, the combination of a base for supporting a structure comprising a pair of coaxial cylinders to be bored, a pair of frames adapted to be removably secured to and supported by the outer ends of said cylinders, a pair of boring-bars carried by the frames respectively in coaxial alignment and driven one from the other, tool-carriers mounted on the bars, mechanism for driving one of said bars and means carried by each frame for automatically feeding the tool-carrier on the bar which is carried thereby.

30 4. In mechanism for re-boring cylinders, the combination of a base for supporting a structure comprising a pair of cylinders to be bored, a pair of frames adapted to be removably connected to and supported by said cylinders, a pair of boring-bars carried by the frames, mechanism for driving one of the bars, and tool-carriers mounted on the bars, said bars being insertable with the carriers thereon into the cylinders from opposite ends thereof and driven one from the other.

35

40

5. In mechanism for re-boring cylinders, the combination of a base for supporting a structure comprising a pair of coaxial cylinders to be bored, a pair of frames adapted to be removably connected to and supported by the outer ends of said cylinders, a pair of boring-bars carried by the frames in coaxial alignment, mechanism for driving one of the bars, and tool-carriers mounted on the bars, said bars being insertable with the carriers thereon into the cylinders from opposite ends thereof and driven one from the other.

6. In mechanism for re-boring cylinders, the combination of a base for supporting a unitary structure comprising a pair of coaxial and spaced cylinders, a pair of frames adapted to be removably secured to and supported by the outer ends of said cylinders, a pair of boring-bars carried by the frames in coaxial alignment, tool-carriers mounted on said bars, mechanism for driving one of the bars, and a drive coupling between said bars and disposed inwardly of the cylinders, said coupling being adapted to permit the bars with the carriers thereon to be with-

drawn from the opposite ends of the cylinders.

7. In mechanism for re-boring cylinders, the combination of a base for supporting a unitary structure comprising two pairs of coaxial cylinders to be bored, two pairs of boring-bars, the bars of each pair being driven one from the other and insertable endwise into the cylinders, a pair of frames, each for carrying two of said bars, said frames being adapted to be removably secured to and supported by the opposite ends of the cylinders, tool-carriers mounted on the bars, and mechanism for driving one bar of each pair of bars.

8. In mechanism for re-boring cylinders, the combination of a base for supporting a unitary structure comprising two pairs of coaxial cylinders to be bored, two pairs of boring-bars, the bars of each pair being driven one from the other and insertable endwise into the cylinders, a pair of frames, each for carrying two of said bars, said frames being adapted to be removably secured to and supported by the opposite ends of the cylinders, tool-carriers mounted on the bars, mechanism for driving one bar of each pair of bars, and means carried by each frame for automatically feeding the carriers on the bars which are carried thereby. 95

9. In mechanism for re-boring cylinders, the combination of a base for supporting a unitary structure comprising two pairs of coaxial cylinders to be bored, two pairs of boring-bars, the bars of each pair being driven one from the other and insertable endwise into the cylinders, frames adapted to be removably secured to and supported by the outer ends of said cylinders and by which the bars are carried, tool-carriers mounted on the bars, and means for driving one bar of each pair of bars comprising motors mounted on the base.

10. In mechanism for re-boring cylinders, the combination of a base for supporting a cylinder to be bored, a frame adapted to be removably secured to and supported by the cylinder, a boring-bar carried by the frame, a tool-carrier mounted on the bar, a motor mounted on the base, and gearing for driving the bar from the motor, said gearing being mounted on the frame and pivoted to swing into engagement with the motor when the frame has been secured in its operative position.

11. In a re-boring machine of the character described, the combination of a pair of supporting head-frames provided with means whereby they may be secured to the outer ends of a pair of cylinders respectively, re-boring bars mounted in said frames insertable into the outer ends of the cylinders respectively, mechanism for driving one of the boring-bars comprising a motor and gearing, and a detachable connection in the gearing.

ing for permitting the frame to be removed independently of the motor.

12. In a re-boring machine of the character described, the combination of a pair of supporting head-frames provided with means whereby they may be secured to the outer ends of a four-cylinder structure, a pair of re-boring bars mounted in each of said frames, insertable into the outer ends of

the cylinders respectively, mechanism for driving one of the boring-bars comprising a motor and gearing, and a detachable connection in the gearing for permitting the frame to be removed independently of the motor.

Signed at Battle Creek, Michigan, this 28 day of August, 1924.

BURT J. FARR.

MOSES H. WESTBROOK.
